(57) **CLAIM**

The ornamental design for a strain relief device for a hose, as shown and described.

DESCRIPTION

FIG. 1 is a front perspective view of a strain relief device for a hose;

FIG. 2 is a front perspective view of the strain relief device rotated 90° on the longitudinal axis of the strain relief device for a hose from the view shown in FIG. 1;

FIG. 3 is a side view of the strain relief device for a hose; FIG. 4 is a side view of the strain relief device for a hose rotated 90° on the longitudinal axis of the strain relief device from the view shown in FIG. 3;

FIG. 5 is a front view of the strain relief device for a hose; FIG. 6 is a rear view of the strain relief device for a hose; FIG. 7 is a rear perspective view of the strain relief device for a hose; and,

FIG. 8 is a rear perspective view of the strain relief device for a hose rotated 90° on the longitudinal axis of the strain relief device from the view shown in FIG. 7.

The broken lines in the drawings depict portions of the strain relief device for a hose that form no part of the claimed design.
